UNITED STATES PATENT OFFICE

2,517,747

BRAKE BEAM AND METHOD OF MAKING

Loren L. Whitney, Hammond, Ind., assignor to
American Steel Foundries, Chicago, Ill., a corporation of New Jersey

Application September 18, 1948, Serial No. 49,935

12 Claims. (Cl. 188—223.1)

1

This invention relates to railway brake beams and more particularly to a novel welded truss type beam of economical construction and capable of withstanding the severe stresses of railway service.

A general object of the invention is to devise a welded beam which may be economically fabricated by welding a tension member to the front web of a channel-section or U-section compression member.

A more specific object of the invention is to weld the tension member to the forward surface of the compression member front web by welding through the rear surface of said web between the top and bottom webs of the compression member.

Another object of the invention is to devise an economical method and means for reinforcing the welded connection between the tension and compression members.

Still another object of the invention is to eliminate leakage of weld metal by damming the connection between the tension and compression members at their contacting areas.

A further object of the invention is to provide a truss having rigid connections of novel form to the brake heads of the beam.

The foregoing and other objects and advantages of the invention will become apparent from a consideration of the following specification and the accompanying drawings, wherein:

Figure 1 is a fragmentary top plan view of a brake beam constructed according to the invention;

Figure 2 is an end view of the beam shown in Figure 1;

Figure 3 is a fragmentary top plan view of the brake beam truss structure with the brake head removed;

Figure 4 is an end view taken from the right of Figure 3;

Figure 5 is a top plan view of a modified form of truss structure; and

Figure 6 is an end view taken from the right of Figure 5.

Describing the invention in detail and referring first to the brake beam shown in Figures 1 and 2, the beam comprises a truss structure including a compression member 2 of U-section or channel-section having a front web 4 and top and bottom webs 6 and 8. The truss also comprises a tension member 10 preferably of standard round section steel bar having a uniform cross-section from end to end thereof. The out-

2

board end of the tension member is bent or deformed as at 12.

As best seen in Figures 3 and 4, the end portion 12 of the tension member is sleeved within a complementary cylindrical opening or hole 14 within a steel filler block 16 having an inboard extension 18 affording a flat seat as at 20 between the block and the forward surface of the front compression member web 4 from the outboard end 10 to the inboard end of the tension member portion 12.

The block 16, the portion 12, and the front web 4 are welded together from the rear surface of the web 4, as indicated in phantom lines at 22 (Figures 3 and 4). The weld is preferably made by the process disclosed in United States Letters Patent No. 2,043,960, issued June 9, 1936, to Union Carbide and Carbon Corporation. The weld connection at 22 extends lengthwise of the web 4 from a point closely adjacent the outboard end of the block 16 to a point closely adjacent the inboard end of the extension 18, the block acting as a dam to prevent escape of the molten weld metal from between the web 4 and the portion 12 and also affording an unusually rigid connection therebetween.

Referring again to Figures 1 and 2, a brake head, generally designated 24, is provided at each end of the beam, the head having a front wall 26 adapted to afford a seat on its forward surface for a brake shoe 28 (Figure 2). The brake head also comprises top and bottom rear walls 30 and 32 connected to the front wall 26 by substantially vertical walls 34 and 36. The top and bottom walls 30 and 32 are secured as by rivets 38 to the top and bottom compression webs 6 and 8 respectively, and are offset as at 40 to afford spaced top and bottom seats for the front compression member web 4. The top and bottom brake head walls 30 and 32 forwardly of the shoulders 40 define a socket or recess 42 receiving the block 16 and the tension member end portion 12, and forwardly of the recess 42 the brake head walls 30 and 32 merge with the front wall 26 and are formed with a conventional hanger socket 44 affording reception for an associated brake beam hanger (not shown).

As seen in Figure 2, the beam is provided at its transverse center line with a strut 46 connected in conventional manner between the tension and compression members 10 and 2, the strut being provided with the usual brake lever slot 48 and pin hole 50.

In fabricating the above-described beam, the tension member 10 is bent, or otherwise deformed,

to form the end portion 12 extending approximately parallel to the compression member web 4. The portion 12 is then fitted within the complementary opening 14 of the block 16 and the block is then seated at 20 against the web 4 and is clamped in position during the welding process which is normally performed with the tension member 12 below the compression member 2 and the compression member webs 6 and 8 disposed approximately in a vertical position to accommodate a weld along the rear surface of the web 4. After the weld has been completed, the brake head 24 is riveted in place, as shown in Figures 1 and 2.

A modified truss structure is shown in Figures 5 and 6 wherein parts corresponding to those of Figures 3 and 4 are identified by corresponding numerals. In the modification of Figures 5 and 6, the front compression member web 4 is slotted as at 52 and the rear margin of the opening 14 in the block 16 is open to accommodate insertion of the tension member portion 12 into the slot 52 when the block 16 is seated as at 20 against the forward surface of the front compression member web 4.

It may be noted that the vertical longitudinal center line of the portion 12 is disposed inwardly of the opening at the rear edge of the hole 14 so that the block 16 will remain in assembled relationship during the welding at 22.

The truss structure shown in Figures 5 and 6 is welded in the same manner as that shown in Figures 3 and 4 with the tension member 10 below the compression member 2 and the webs 6 and 8 approximately vertical. The tension member portion 12 is first inserted within the block 16 and the latter is then clamped in the position shown in Figures 5 and 6 against the forward surface of the front web 4 which is, during the welding process, the bottom surface of the web 4, and the weld 22 is then made through the slot 52 from the rear surface of the web 4 between the webs 6 and 8.

After the truss structure has been fabricated, as above described, a brake head is riveted to the truss, as above described in connection with Figures 1 and 2.

I claim:

1. A brake head comprising a compression member having top and bottom webs and a front web, a filler block externally of the space between said top and bottom webs, bearing against the forward surface of said front web and having an arcuate opening extending from the inboard to the outboard end of said block, a tension member of uniform cross-section from end to end thereof having an end portion bent approximately parallel to said front web, said portion being snugly fitted in said opening, a brake head having a cavity receiving said block, said portion and said webs, said brake head having top and bottom rear walls connected to said top and bottom webs, and a welded connection between said front web, said block and said portion, said connection extending lengthwise of said front web and being spaced from but extending adjacent to the inboard and outboard ends of the block.

2. A truss type railway brake beam including a compression member of channel-section having a front web and top and bottom webs extending rearwardly therefrom, a generally rectangular filler block having a flat surface seated against a complementary face on the exterior surface of said front web, a tension member having an arcuate end portion extending generally parallel

to the front web and snugly fitted in a complementary opening through the block, a weld securing said portion, said surface and said face, and a brake head having top and bottom walls connected to the external surfaces of said top and bottom webs respectively, said walls being offset toward each other to afford top and bottom seats bearing against said face above and below said block and to define a cavity complementary to and receiving said block.

3. A brake beam comprising a compression member having top and bottom webs and a front web, a filler block bearing against the forward exterior surface of said front web and having an arcuate opening extending from the inboard to the outboard end of said block, a tension member having an arcuate end portion complementary to and snugly fitted in said opening and extending approximately parallel to said front web, a welded connection between the front web, the block and said portion, and a brake head having a front wall adapted to seat associated brake shoe means and having top and bottom rear walls connected to the top and bottom webs respectively.

4. A brake beam comprising a compression member having top and bottom webs and a front web defining a channel, a filler block bearing against the forward surface of said front web externally of the channel and having an arcuate opening extending from the inboard to the outboard end of said block, a tension member having a portion generally parallel to said front web, said portion being complementary to and snugly fitted in said opening, a weld connecting said front web to said block and said portion, and a brake head connected to the compression member, said block having an extension spaced from the forward surface thereof and extending inboard beyond the inboard margin of said head.

5. A method of fabricating a railway truss comprising the steps of deforming the end of an arcuate section tension member approximately parallel to the front web of a U-section compression member, then snugly fitting a filler block on the deformed end of the tension member and seating said block against the external surface of said web along complementary substantially flat areas to eliminate leakage of molten weld metal between the block and the web, then welding the block and said end to the web from the rear surface thereof, and then attaching a brake head to the compression member.

6. A truss type railway brake beam including a truss structure comprising a compression member having an internal channel and a substantially vertical flat surface at its forward edge externally of the channel, a filler block having a flat surface complementary to and seated against the first-mentioned surface, a tension member extending generally parallel to said surface through a complementary opening in said block, a welded connection between said surfaces and said tension member, and a brake head secured to said structure.

7. A brake beam comprising a truss structure including a compression member with a front web and top and bottom webs extending rearwardly therefrom and defining a channel, a filler block seated against the forward surface of said front web externally of the channel, a tension member extending generally parallel to the front web and through a complementary opening in the block, a welded connection between the front web, the block and said portion, and a brake head carried by said structure.

8. A method of fabricating a railway brake beam comprising the steps of deforming the end portion of an arcuate section tension member approximately parallel to the front surface of a compression member web having a slot, then snugly fitting a filler block on the deformed end portion of the tension member, then seating said block against the forward surface of said web along complementary substantially flat areas and inserting the tension member into the slot, and then welding the tension member and block to said web.

9. A brake beam comprising a truss structure including a compression member having an internal channel, a filler block seated against the forward surface of said member externally of the channel, a tension member extending through a complementary opening in the block, a welded connection between the block, the tension member and the compression member, and a brake head carried by said structure.

10. A truss type railway brake beam comprising a compression member having a web with a slot, a filler block seated against the web, a tension member extending through a complementary opening in the block and into the slot, a weld connecting the block to the compression

and tension members, and a brake head carried by the compression member.

11. A method of fabricating a railway brake beam comprising the steps of fitting an end portion of a tension member into a complementary opening of a one-piece filler block, then seating the block against the external surface of a front compression member web, and then welding the web from the rear surface thereof to the block and the portion.

12. A method of fabricating a railway brake beam comprising the steps of fitting the end of a tension member into a one-piece filler block, and then welding the block to a channel compression member externally of its channel.
